Specification for Design.

Patented Mar. 19, 1912.

Application filed December 18, 1911. Serial No. 666,610. Term of patent 7 years.

To all whom it may concern:

Be it known that we, THOMAS R. KEN-
NEDY and EDWARD J. KING, citizens of the
United States, residing at Rochester, in the
county of Monroe and State of New York,
have invented a new, original, and ornamental
Design for Stoves, of which the accompanying
drawing is a representation.

The figure is a perspective view of a stove,
showing our new design.

We claim:

The ornamental design for a stove as herein shown.

THOMAS R. KENNEDY.
EDWARD J. KING.
